[57] CLAIM

The ornamental design for a combined tie holder and sleeve therefor, as shown.

DESCRIPTION

FIG. 1 is a front elevational view of a combined tie holder and sleeve therefor showing my new design;
FIG. 2 is a rear elevational view thereof;
FIG. 3 is a front elevational view of the tieholder, the sleeve removed for convenience of illustration;
FIG. 4 is a rear elevational view thereof;
FIG. 5 is a right side elevational view thereof;
FIG. 6 is a left side elevational view thereof;
FIG. 7 is a rear perspective view, the clasp in open position for convenience of illustration;
FIG. 8 is a right side elevational view of the sleeve, the tieholder removed for convenience of illustration; and
FIG. 9 is a left side elevational view thereof.
